Term of patent 14 years

(Cl. D13—1)

FIG. 1

FIG. 2

FIG. 3

FIG. 4

FIG. 1 is a front perspective view of a telephone booth for group use showing my new design;

FIG. 2 is a top plan view, on a reduced scale, of the booth shown in FIG. 1;

FIG. 3 is a front elevational view thereof, on a reduced scale; and

FIG. 4 is a side elevational view thereof, on a reduced scale.

The communication instrument shown in broken lines in FIG. 1 is disclosed for illustrative purposes only.

The dominant features of my new design reside in the portion shown in solid lines on the drawing.

I claim:

The ornamental design for a telephone booth for group use, as shown and described.
